UNITED STATES PATENT OFFICE.

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE.

CYLINDER LOCK.

Application filed June 7, 1926. Serial No. 114,205.

This invention has for its object to provide a driving stem for connecting the lock cylinder with the part to be driven thereby, such stem having universal connection with the lock cylinder to permit it to assume an angular position with respect to the lock.

An object of the invention is to produce such universal joint connection by simple and inexpensive means within the lock-case, insuring against the disconnection of parts and making the structure strong and durable for the intended purposes.

Another object of the invention is to specifically improve upon the construction covered in my pending application for locks, Serial No. 71,350.

With the above and other objects in view the invention consists in the cylinder lock as herein claimed and all equivalents.

Referring to the accompanying drawings in which like characters of reference indicate the same parts in different views,

Fig. 1 is a longitudinal sectional view of a cylinder lock exemplifying this invention;

Fig. 2 is a rear view thereof;

Fig. 3 is a transverse sectional view on the plane of line 3—3 of Fig. 1, and

Fig. 4 is a similar view on the plane of line 4—4 of Fig. 1.

In these drawings, 10 indicates a lock-case having a recess or cylindrical pocket entering it from its front end, in which is fitted a lock cylinder 11 to be turned by means of a key fitting in a key slot 12 thereof. Diametrically opposite grooves 13 in the inner walls of the lock-case receive the tumbler slides 14 of the lock cylinder to prevent the latter from turning, such tumblers being controlled by the key in the usual manner. A thin sheet metal shell 15 fits over the flanged front end of the lock-case and against a reduced shoulder of the cylinder 11 to confine it.

The grooves 13 do not extend to the full depth of the pocket, and the inner end of the lock cylinder is provided with a square socket 16 to loosely receive the end of the square stem 17 for turning it. The stem is held within the driving socket of the lock cylinder by a slotted washer 18 keyed thereon by having the parallel edges of its slot fitting within slots 19 cut through diagonally opposite edges of the stem a short distance from its end which form a reduced neck por-

tion. The stem passes through a flaring opening 20 in the end of the lock-case and the washer is countersunk within a bearing seat formed for it in the bottom of the pocket and is held in its seat by the end of 60 the lock cylinder bearing thereon. The washer turns on its seat, moving with the stem as the latter is turned by the lock cylinder, but the play of the washer within the slots 19 of the stem and the freedom of the 65 end of the stem within the square socket 16 permits the stem to take angular positions as shown by dotted lines in Fig. 1 to accommodate the location of the lock with respect to the part driven thereby without binding 70 and thus constituting in effect a universal joint transmitting the drive through such angular relation. The lock cylinder may be provided with means for limiting its movement, such as a stop lug 21 on the lock-case 75 10 near the washer seat to be passed by a groove or rabbet 22 in the end of the lock cylinder and limiting the turning of the lock cylinder when the ends of said groove 22 engage therewith.

With this invention the driving stem is retained in its driving connection with the lock cylinder and is rotatably mounted in the lock-case by the washer 18 which constitutes a thrust bearing for the stem freely 85 turning with it and permitting any angular position thereof but limiting its endwise movement.

As the lock-case is usually made of die cast metal, the bearing thereagainst formed by the steel bearing washer 18 remaining in its flat surface contact therewith in all angular positions of the stem avoids gouging or cutting the soft metal and thus makes the lock durable.

Obviously the invention is not limited to the details shown as many modifications may be made therein.

What I claim as new and desire to secure by Letters Patent is:

1. A lock comprising a lock-case, a cylinder mounted therein, a driving stem entering the lock-case and having loose driving connection with the cylinder, and a washer mounted on the driving stem and confined 105 within the lock-case to hold the stem in its driving connection with the cylinder, said washer being loose on the driving stem to permit of angular positions thereof with respect to the cylinder.

105

110

2. In a lock, a lock-case, a lock cylinder turning therein, a driving stem entering the lock-case and having driving connection with the lock cylinder, said driving stem having a contracted neck portion, and a bearing washer fitting thereon and confined within the lock-case but having a loose fit on the driving stem to permit of angular positions thereof with respect to the lock cylinder.

3. In a lock, a lock-case, a lock cylinder turning therein, a driving stem entering the lock-case through an opening at the end thereof and having driving connection with the cylinder, said driving stem having a reduced neck portion, and a bearing washer fitting on the reduced neck portion of the driving stem and having a bearing seat within the lock-case at the end of said opening, there being play between the driving stem and the washer to permit of angular positions of the driving stem.

4. In a lock, a lock-case, a lock cylinder turning therein, there being an opening in the end of the lock-case, a square driving stem passing through said opening and having opposite slots therein, and a washer having a slot to loosely fit within the slots

of the driving stem and seated within the lock-case, there being a socket in the end of the lock cylinder having a loose driving fit with the end of the driving stem, the play of said driving stem within the washer and the lock cylinder permitting it to take angular positions with respect to the lock cylinder.

5. In a lock, a lock-case, a lock cylinder turning therein, a driving stem entering the lock-case and having a driving connection with the lock cylinder, said driving stem having opposite slots, and a slotted washer loosely fitting in the slots of the driving stem but keyed to turn with the driving stem, there being a bearing shoulder within the lock-case against which the washer fits, the end of the lock cylinder bearing on the washer to hold it in place but free to turn, and the fit of the washer in the slots of the driving stem being sufficiently loose to permit of angular positions of the driving stem with respect to the lock cylinder.

In testimony whereof, I affix my signature.

EDWARD N. JACOBI.
